Primary Examiner — Paula Allen Greene**CLAIM**

The ornamental design for headset with boom microphone, substantially as shown and described.

DESCRIPTION

FIG. 1 is a front and right side perspective view of a headset with a boom microphone showing our new design, the headset with a boom microphone connected to the left-side housing is a mirror image;

FIG. 2 is a front view thereof;

FIG. 3 is a left side view thereof;

FIG. 4 is a back view thereof;

FIG. 5 is a right side view thereof;

FIG. 6 is a top view thereof;

FIG. 7 is a bottom view thereof; and,

FIG. 8 is a front and left side perspective view thereof. The dotted line portions of the drawings represent environmental structure only and do not form part of the claimed design.
